UNITED STATES PATENT OFFICE.

JOSEPH B. CAMBERS, OF SAN JOSE, CALIFORNIA.

EARTH-SCRAPER.

1,125,464.

Specification of Letters Patent. Patented Jan. 19, 1915.

Application filed March 19, 1914. Serial No. 825,856.

To all whom it may concern:

Be it known that I, JOSEPH B. CAMBERS, a citizen of the United States, residing at San Jose, in the county of Santa Clara and State 5 of California, have invented certain new and useful Improvements in Earth-Scrapers, of which the following is a specification.

My invention relates to earth scrapers, 10 and more particularly to that general class known as field or road scrapers.

The object of my invention is to provide an earth scraper of durable and simple construction, capable of being used in a field 15 or on a road or in any other place where an earth scraper may be required, without the necessity of disturbing the arrangement or in any manner altering or changing the construction thereof.

20 A further object of my invention is to provide an earth scraper that will require no levers or lifting bars to handle in operating said scraper, and one in which the earth scraper is operated from a platform 25 by the weight of the operator, giving thoroughly reliable service under all conditions.

20 A further object of my invention is to provide an earth scraper and means for supporting said earth scraper upon a pair of 30 supporting wheels, the arrangement of parts also include the relative manner in which the operator's or driver's platform is disposed whereby the weight of the driver will be substantially balanced upon the wheel- 35 supports.

30 A further object of my invention is to provide an earth scraper which includes a novel coöperative arrangement of a locking 40 latch or detent mechanism for maintaining the scraper in a relatively fixed position while carrying the load to the dump, and also for maintaining the scraper in a fixed position up clear of the ground when said 45 scraper is not in use.

45 In its more subordinate features my invention embodies certain details of construction and novel combination of parts, all of which will be hereinafter more fully described, and particularly pointed out in 50 the appended claim, reference being had to the accompanying drawings, in which—

55 Figure 1 is a plan view of my earth scraper, parts being broken away. Fig. 2 is a sectional view on line A—A of Fig. 1, parts being broken away. Fig. 3 is a detail perspective view showing section on line

D—D of Fig. 1, parts being broken away. Fig. 4 is a rear elevation of operator's seat in position, parts being broken away. Fig. 5 is a detail plan view of the platform 60 showing position of locking and unlocking foot pedals and hinge attachment to scraper, parts being broken away. Fig. 6 is a sectional view on line B—B of Fig. 5, parts being broken away. Fig. 7 is a sectional 65 view on line C—C of Fig. 5, parts being broken away. Fig. 8 is a perspective view of the right-hand cam of the locking device. Fig. 9 is a perspective view of one of the braces to which the cutting blade is attached, parts being broken away. 70

Referring to the accompanying drawings, in which like characters indicate like parts in all of the figures. 1 indicates the platform to which is attached axle 2, the same 75 being fastened to the under side of platform 1 in any suitable manner. Wheels mounted on said axle 2 are shown at 3. These wheels may be made of any suitable material and of any size required. Fastened to the front 80 end of platform 1 by hinge attachments 4 is earth scraper 5. Fastened to the rear end of said platform 1 are brace attachments 6, one on each side thereof, the same being fastened to platform 1 by bolts shown 85 at 7. These brace attachments 6 are bent upward a distance for the purpose of extending the rear end of said platform upward a distance for the purpose of clearing the ground when the scraper 5 on the front 90 end of the platform 1 is raised up clear of the ground by the weight of the operator stepping on plank 8 which is bolted to brace attachments 6 by bolts 9. An iron railing shown at 10 is fastened to platform 1 at 11. 95

The upper portion of said railing 10 extends out over the front end of platform 1 a distance for the purpose of a hand rest when the operator steps forward of axle 2 for the purpose of entering the scraper 5 into the 100 earth to be scraped. This railing 10 has center rods 12, longitudinal with platform 1 and up a distance from platform 1, one on each side thereof. This center rod 12 is for the purpose of adjusting the operator's seat 105 13 thereon, the same being fastened to bent rods 14 which engage center rods 12 by hooks shown at 15. Connected to bent rods 14 are swivel rods 16 which extend downward to platform 1 and engage with stay 110 strip 17. These strips are fastened to platform 1 in any suitable manner, one on each

side thereof, and are for the purpose of holding said seat 13 in the proper position by swivel rods 16 when the same is in use. The above construction allows the seat 5 to be placed forward or backward of said axle 2 on either side of said platform required, and also the seat may be turned up out of the way and fastened to railing 10 when not in use. Fastened to said scraper 10 5 is draft pole 18, the same being held in place by bolts shown at 19. Braces are shown at 20 fastened to draft pole 18 by bolts 21. The rear end of said braces 20 are bent outward a distance as shown at 22 15 and inserted through a slot cut through scraper 5 as shown at 23, Fig. 3, and fastened to longitudinal bar 24 by bolts shown at 25, said longitudinal bar 24 being fastened to a plurality of upright bars 26 by bolts 27, said upright bars being fastened to the back of scraper 5 by bolts 28. The heads of said bolts 28 are counter-sunk into the face of scraper 5 thereby leaving the face of said scraper 5 smooth. The lower 25 longitudinal end of upright bars 26 are bent upward a distance as shown at 29, having a slot 30 cut through said bent up portion as shown in Fig. 9. This slot 30 is for the purpose of fastening and adjusting cutting 30 blade 31 to the bottom edge of scraper 5. This cutting blade 31 is made of steel of the proper width, length and thickness, having two beveled edges for the purpose of reversing the same when required and is fastened 35 to upright bars 26 by countersunk bolts 32. On the back of scraper 5 and near the lower end thereof is attached adjusting rods 33 which extend upward and through platform 1 as shown at 34 one on each side 40 thereof. Said adjusting rods 33 have a plurality of notches cut in the upper side thereof as shown at 35 adapted to engage quarter circle plates 36 which have notches cut in the ends thereof to correspond with the 45 notches 35 cut in rods 33. These rods 33 are for the purpose of adjusting scraper 5 in any position required and are held in place by cams 37 fastened to cam shaft 38. This cam shaft 38 extends across the under side 50 of platform 1 and is held in place by bearings 39 bolted to the under side of platform 1. Cam 37 on the right hand side of platform 1 has two arms as shown at 40 and 41. Connected to arm 40 is rod 42, the 55 same passing up through platform 1 to which is fastened pedal 43. Connected to arm 41 is rod 44, the same passing up through platform 1 to which is fastened pedal 45. Fastened to platform 1 and directly under adjusting rods 33 are sheave 60 wheels 46, the same being for the purpose of a bearing for rods 33 when the same are

thrown out of engagement with quarter circle plates 36. Stops are shown at 47 one on each side of platform 1, bolted to the 65 underside thereof by bolts shown at 48, these stops may be made of iron or any other suitable material, and are for the purpose of preventing scraper 5 from taking any further backward position. End plates 70 fastened to scraper 5 are shown at 49, one on each end of scraper 5, and are for the purpose of retaining the load until the same is required to be unloaded.

The operation of my earth scraper is as 75 follows: The operator standing on platform 1 sets the scraper in the required position and locks the same by pressing down on pedal 43, which throws rods 33 into engagement with quarter circle plates 36 by cams 80 37, and thereby locking scraper 5 in position. The weight of the operator stepping forward of axle 2 inserts the scraper 5 into the earth as the horses advance. When the load is required to be unloaded the operator 85 steps back of axle 2 a distance which raises scraper 5 and unloads the same gradually or at once as required. To change the position of scraper 5 the operator presses down on pedal 45 which throws cams 37 out 90 of engagement with rods 33, and said rods drop back to sheave wheels 46 allowing the scraper 5 to be adjusted into any other position that may be required. Seat 13 may be adjusted forward or backward on center 95 rods 12 and platform 1 as the operator may require.

Having thus described my invention, what I claim and desire to secure by Letters Patent, is—

The combination of a platform, a scraper attached thereto, adjusting rods attached to said scraper one on each end thereof adapted to adjust said scraper in position, said adjusting rods having a plurality of notches 105 cut in the upper sides thereof adapted to engage quarter-circle plates, said quarter-circle plates having notches cut in the ends thereof adapted to engage said adjusting rods, a plurality of cams, a shaft to which 110 said cams are fastened, one of said cams having two arms, rods connected to said cam arms, pedals connected to said rods adapted to operate said cams and lock said adjusting rods in place as and for the purpose described.

In testimony whereof I affix my signature in presence of two subscribing witnesses, this 14th day of March, 1914.

JOSEPH B. CAMBERS.
